(57) **CLAIM**

The ornamental design for a mobile phone, as shown and described.

DESCRIPTION

FIG. 1 is a front perspective view of a mobile phone showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof; and,

FIG. 9 is an enlarged view of the encircled portion shown in FIG. 2.

In FIGS. 1–6 and 8–9, the solid lines that are immediately adjacent the unshaded front and rear surfaces are boundaries of the claimed design. The unshaded front and rear surfaces bounded by these solid lines form no part of the claimed design. In FIGS. 2 and 9, the dot-dash broken lines encircle and indicate a portion of the claimed design that is shown on an enlarged scale in FIG. 9. All other broken lines throughout the drawing figures depict unclaimed environmental portions of the mobile phone. The broken lines form no part of the claimed design.
